UNITED STATES PATENT OFFICE.

IRA M. ABRAM, OF DUGGER, INDIANA, ASSIGNOR OF ONE-FOURTH TO CLAIRE THOMSON,
OF FARMERSBURG, INDIANA.

CAR PUSHER.

Application filed August 1, 1922. Serial No. 579,051.

To all whom it may concern:

Be it known that I, IRA M. ABRAM, a citizen of the United States, residing at Dugger, in the county of Sullivan and State 5 of Indiana, have invented certain new and useful Improvements in Car Pushers; and I do declare the following to be a full, clear, and exact description of the invention, such as will enable others skilled in the art to 10 which it appertains to make and use the same.

This invention relates to an improved car pusher and one object of the invention is to provide a device which will be used for imparting movement to cars which are standing upon a track, the device being provided with an improved frame construction and an improved lever and also provided with improved rail gripping jaws and 20 with an improved type of wheel-engaging shoe.

Another object of the invention is to so construct the rail-engaging jaws that when the device is moved to lift the frame, the 25 jaws may be moved to an inoperative position and when the lever is swung downwardly in an operative direction, the jaws may be brought into close gripping engagement with the tread portion of the rail and 30 the device thus prevented from having any tendency to move longitudinally of the rail.

Another object of the invention is to so mount the lever and wheel-engaging shoe that when the lever is swung downwardly 35 in the operative direction, the shoe may be tilted and thus brought into close contact with the wheel so that the wheel engaged by the shoe may be given rotary movement to start a freight car rolling along a track.

Another object of the invention is to so construct this pusher that when in use, it may be operated by simply swinging the actuating handle or lever, downward swinging 40 movement of the lever handle causing the shoe to be moved to rotate the wheel and thus impart movement to the car, and upward movement of the lever handle causing 45 the device to be moved longitudinally of the track into proper operative relation 50 to the car wheel.

Another object of the invention is to so construct this car pusher that the housing with which the lever handle is pivotally connected, may be loosely mounted for sliding 55 vertically upon the frame with which the

rail gripping jaws are pivotally connected, this housing being provided with abutment rollers for engaging the upper end portions of the jaws and moving the jaws to an open or a closed position according to the 60 direction in which the housing is moved. When the handle moves upwardly, the housing is also moved upwardly to release the jaws and permit movement of the device to an operative position with respect to the car 65 wheel, and when the handle is swung downwardly to impart pushing movement to the wheel engaging shoe, the jaws are brought into tight gripping engagement with the rails, thus preventing the device from moving 70 out of the proper position upon the rails.

Another object of the invention is to provide a device formed from a plurality of parts which will be firmly held together but 75 may be readily taken apart in order to replace any worn or broken parts.

This invention is illustrated in the accompanying drawings, wherein:

Figure 1 is a view showing the device in 80 side elevation and shown as it would appear when imparting movement to a car.

Figure 2 is a view similar to Fig. 1 showing the lever handle swung upwardly and ready for the next pushing movement. 85

Figure 3 is a vertical sectional view through the device when in the position shown in Fig. 2.

Figure 4 is a top plan view of the improved device. 90

Figure 5 is a sectional view taken along the line 5-5 of Fig. 1.

Figure 6 is a sectional view taken along the line 6-6 of Fig. 2.

This car pusher is to be used in connection 95 with a rail R and will engage the wheels W of a car so that the wheels can be caused to rotate forwardly and thus the car caused to move along the track. The jaws 1 which are to firmly grip the tread portion of the rail 100 and are pivotally connected with bearing arms 2 which extend transversely of the base portion or bar 3 of a frame which forms the body portion of the car pusher. This bar 3 is provided at its forward and rear 105 ends with rollers 4 which rest upon the tread of the rail so that the device can be easily moved along the rail as the car is pushed along the track. An arm 5 which is in the form of a fork as shown in Fig. 5 ex- 110

tends upwardly from the bar 3 and is bent adjacent its connection with the bar 3 so that this arm or fork 5 extends upwardly to the rear of the shank portions 1' of the jaws 5. The shanks 1' of the jaws are curved longitudinally as clearly shown in Fig. 6 and these shanks extend between the forward and rear plates 6 and 7 which form a housing movable vertically. These plates 10 are connected by bolts 8 and between the plates there has been provided spacing rollers to retain the plates in the desired spaced relation when the securing nuts are tightened. Rollers 9 are mounted on certain 15 of these spacing sleeves to engage the curved shanks of the jaws and act to impart swinging movement to them when the device is in use. It should be further noted that cleats 10 are mounted upon the outer end portions 20 of certain of these bolts 8 to engage the arms of the fork 5 and thus guide the vertical movement of the housing. A bearing bracket 11 is carried by the bolts 8' between the forward and rear plates of the housing 25 and is provided with depending arms 11' between which the lever handle 12 is pivotally mounted by means of a pin 13. This lever handle 12 extends rearwardly through a slot 14 in the rear plate 7 of the housing 30 and between the arms of the fork 5 and has its forward end portion extending through a slot 15 formed in the forward plate 6 of the housing. It will thus be seen that this lever can be rocked upon the pivot 13. At 35 the forward end of the lever, there is provided a hook 16 for engaging the upper end of an abutment plate or strip 17 which is adjustably carried by a standard 18 through the medium of a bolt 19 which passes 40 through a slot formed in the standard. When the lever is swung upwardly, this hook 16 engages the strip 17 thereby providing a fulcrum so that the housing will be moved upwardly. As the housing moves 45 upwardly, the shanks of the jaws will be moved toward each other and the jaws will be moved to a releasing position. At their free ends, these shanks have been provided with spurs 20 to engage the bolts 8 at the 50 sides of the housing and limit upward movement of the housing. Therefore, the housing cannot move upwardly a sufficient distance to move out of proper engagement with the shanks of the jaws. With the lever handle swung upwardly to the position shown in Fig. 2, the device can be easily moved along the rail into proper position for the next pushing stroke. The wheel-engaging shoe 21 is curved longitudinally so 55 as to fit in close contact with the wheel and has its lower end portion pivotally mounted between the forward end portions of links 22 which extend in diverging relation and have their rear ends pivotally connected 60 with bearing ears 23 which extend out-

wardly from the forward face of the plate 6 of the housing. Links 24 which are in the form of turn buckles are pivotally connected with the upper end portion of the shoe and forward end portion of the lever handle 12 and it will be readily seen that when the lever handle is swung vertically, the shoe will be brought into close contact with the wheel. The shoe will be swung upwardly and forwardly, thereby applying a turning movement to the wheel. 70

When this device is in use, it will be placed upon a rail adjacent one of the wheels of the car to be moved and with the lever handle swung upwardly to lift the housing and thus swing the jaws out of an operative position, pressure will be applied to bring the lower end of the shoe into engagement with the car wheel. The lever handle can then be swung downwardly and in so doing, the jaws will be brought into tight gripping engagement with the rail and the shoe will be swung into engagement with the wheel of the car. Continued downward pressure will 80 impart upward movement to the shoe and as the shoe moves upwardly, with its upper end portion swinging forwardly as it moves upwardly, rotary movement will be imparted to the car wheel. After the lever handle has been swung downwardly its full extent, 85 it will again be swung upwardly and in so doing the shoe will have its upper end portion swung away from the car wheel and as the hook engages the prop 17, the housing will be moved upwardly to swing the jaws out of gripping engagement with the rail. The frame or carriage portion of this device can then move forwardly under the action 90 of the pressure exerted when swinging the lever handle upwardly so that the device follows the car and is moved into the proper position for the shoe to properly engage the car wheel when the handle is again swung downwardly. It will therefore be evident 95 that the device will operate very efficiently since it will be firmly held in engagement with the rail and the shoe brought into very good engagement with the wheel while the handle is moving downwardly and the jaws will be released from the rail and the device 100 moved forwardly upon the rollers 4 while the lever handle is swinging upwardly. When it is desired to take the device apart to repair or replace any portions, it is simply necessary to remove the bolts which act as 105 fasteners, and the device can be easily and quickly taken apart and either repaired or new pieces supplied and the device then put together again. 110

I claim:

1. A car pusher comprising a carriage, rail engaging jaws pivoted to the carriage and having upwardly extending shank portions, a housing slidable vertically of the carriage for moving the jaws into and out 115 120 125 130

of an operative position and limited in its upward movement by the shanks, a wheel-engaging shoe, links pivotally connected with the housing and lower end portion of said shoe, a lever pivotally connected with the housing and extending forwardly and rearwardly thereof, links pivotally connected with the forward end of said lever and upper end of said shoe, and a fulcrum 10 carried by said carriage and engageable by the forward end portion of said lever to cause raising of the housing when the rear end portion of the lever is swung upwardly.

2. A car pusher comprising a carriage, rail engaging jaws pivoted to the carriage and having upwardly extending shank portions, a housing slidable vertically of the carriage for moving the jaws into and out of an operative position and limited in its 15 upward movement by the shanks, a wheel-engaging shoe, links pivotally connected with the housing and lower end portion of said shoe, and an operating element for the shoe and housing pivoted to the housing and having link connection with the upper end portion of the shoe, the operating element being engaged with a fulcrum element carried by said carriage when swung in one direction to impart upward movement to the housing 20 and move the jaws to an inoperative position.

3. A car pusher comprising a carriage, rail engaging jaws pivoted to the carriage and having upwardly extending shank portions, a housing slidable vertically of the carriage, the shanks of the jaws being extended through the housing and the housing having elements engaging the shanks to limit upward movement of the housing and 25 swing the jaws into and out of an operative position as the housing moves, a lever handle extending through the housing and pivotally mounted therein, a fulcrum element carried by the carriage in front of said housing, the lever having its forward end provided with a hook element for engaging the fulcrum to cause upward movement of the housing when the lever is swung upwardly, a vertically disposed wheel engaging shoe and links pivotally connected with 30 the end portions of the shoe, the lower links

being pivoted to the housing and the upper links being pivoted to the forward end of the lever.

4. The structure of claim 3 having the 55 fulcrum in the form of a standard having a lower portion carried by the carriage and an upper portion connected with the lower portion for vertical adjustment and engageable by the hook at the forward end of the 60 lever.

5. The structure of claim 1 having the 65 housing provided with spaced forward and rear plates and cam rollers between the plates, the jaws having their upwardly extending shanks curved longitudinally and extending through the housing between the plates and engageable with the rollers.

6. The structure of claim 1 having the 70 housing provided with spaced forward and rear plates and cam rollers between the plates, the jaws having their upwardly extending shanks curved longitudinally and extending through the housing between the plates and engageable with the rollers, the 75 shanks having their free end portions extended to limit upward movement of the housing.

7. The structure of claim 1 having the 80 housing provided with spaced forward and rear plates and having vertical slots receiving the lever, fasteners holding the plates in spaced relation, a bearing for the lever carried by one of said fasteners, and a fork portion extending upwardly upon opposite 85 sides of the lever, the rear plate being slidably connected with said fork.

8. The structure of claim 1 having the 90 carriage formed as a bar for extending longitudinally of a rail, rollers carried by said bar, and a fork extending upwardly from the bar intermediate its length, the jaws being pivotally connected with opposite 95 sides of the bar and having their shank portions extending upwardly and the housing having sliding connection with the fork provided with spaced forward and rear plates between which the jaw shanks extend.

In testimony whereof I have hereunto set my hand.

IRA M. ABRAM.
